UNITED STATES PATENT OFFICE.

JAMES H. GRAY, OF NEW YORK, N. Y.

ELECTRODE FURNACE.

Application filed July 31, 1920. Serial No. 400,489.

To all whom it may concern:

Be it known that I, JAMES H. GRAY, a citizen of the United States, residing in the city, county, and State of New York, have 5 invented certain new and useful Improvements in Electrode Furnaces, of which the following is a specification.

In my application for United States Patent No. 289,567 filed April 12, 1919, I have 10 described a mechanism for supporting and adjusting the electrode or electrodes of an electric furnace, which permits the mounting of the motor or other source of power on a stationary or other structure outside of 15 the furnace itself so that the motor will not partake of the tilting movement of the furnace; the mechanism being designed at the same time to hold the electrodes in substantially the same position with reference to the 20 furnace when the furnace is tilted as when it is upright.

The present invention covers a specifically different arrangement for securing the same result.

25 The accompanying drawings illustrate an embodiment of the invention.

Figs. 1, 2 and 3 are respectively a front and side elevation and a plan of the furnace, omitting parts which are not directly 30 related to the furnace.

The furnace 1 is oblong in shape with a discharging spout 2 at the forward side and charging doors 3 at opposite ends. The bottom of the furnace is provided with rockers 35 4 rolling on tracks 5 so that it may be tilted forward to discharge it, or returned to its upright position for charging and operation. The foregoing parts may be of any usual or suitable design, a variety of constructions 40 being known by which the furnace can be tilted.

Three electrodes 6, 7 and 8 are arranged on a line lengthwise of the furnace and extend downward through cooling boxes 9 in 45 the roof of the furnace. Each electrode is clamped in a holder 10 which is extended to the rear and connected to the flexible cables 11 which supply it with current. The furnace, in rocking, turns about a pivotal axis 50 12 (Fig. 2) and at the same time moves bodily forward.

The furnace illustrated is for a three-

phase current and is for treating steel or iron. The electrodes are quite heavy, each weighing over two tons in the larger furnaces.

They have to be lowered or raised for the purpose of striking or breaking the arc, and during the operation of melting or treating steel they are moved upward or 60 downward short distances for the purpose of increasing or decreasing the length of the arc. Heretofore they have generally been supported by an overhead structure mounted on the furnace and movable upward and downward, or by cables passing over sheaves on the overhead structure and leading to winding motors mounted on the back or side of the furnace. Such arrangements put an excess weight on the shell 65 of the furnace and require heavy auxiliary supporting members. Also the heat and fumes coming from the furnace are destructive to the motor and to the gearing generally used for reducing the speed between 70 the motor and the electrodes. The mounting of the motor or other source of power on an outside support avoids these disadvantages.

In the construction illustrated I provide 80 winches 13, 14 and 15, one for operating each of the electrodes, and mount these on a fixed wall 16 at the back of the furnace. Each of these winches may be operated by a 85 separately controlled motor arranged as in my application No. 289,567 or by any other suitable or usual means.

A flexible connection extends from each winch to its electrode and is so designed that the electrode will be held in substantially the same position with reference to the furnace when the furnace is tilted as when it is upright; and will preferably be held in substantially the same position with reference to the furnace throughout the tilting movement.

In the case illustrated an overhead platform 17 mounted on the furnace carries supports for three sets of guide pulleys, one set for each electrode. The electrode 8 for 100 example is supported by means of cables 18 and 19 attached at their lower ends 21 and then downward at the side of the furnace, and the cable 19 running over pulleys 22

- and 23 and then down alongside the cable 18. The cables 18 and 19 are connected to an equalizing lever 24 from which a connection runs to the winch 13 corresponding to this electrode. The connection illustrated comprises a cable with a portion 25 extending to a pulley 26 and passing around the same and continued in a portion 27 which is connected to a rod 28 sliding in a guide 29 and connected to another cable which passes directly to the winch 13.
- A similar arrangement is provided for each of the other electrodes 7 and 6, the connections for each electrode passing around the separate pulleys 26 and to other respective winches. The pulleys 26 are mounted on a stud 30 projecting sidewise from the rocker 4 at this side of the furnace.
- 20 The sheaves 26 are so located that when the furnace is rocked there is no substantial motion of the electrodes with respect to the furnace, that is their supporting cables are not shortened or lengthened.
- 25 The sheave is located at such a point that the intersection of its periphery with the radius of the rocker will have a very slight horizontal motion just sufficient to make up for the amount of cable (the part 27) which is unwrapped from the sheave and wrapped on it again during a tilting forward and backward. The length of the cable between the winch and its point of engagement with the pulley 26 lies in a position which is so nearly horizontal that the successive positions of this part of the cable are practically parallel; and the balancing of the wrapping and unwrapping effect about the pulley 26 as above explained results in the practical elimination of any lifting or lowering action of the electrodes during a tilting position.
- For example, supposing the rocker 4 to have a radius of eight feet and the pulley 26 to have a radius of ten inches. The center of the pulley will be located along the radius 31 of the rocker which lies at an angle with the vertical radius 32 equal to one-half the total angle through which the furnace is tilted; or twenty degrees in the case illustrated in which the furnace is designed to be tilted forty degrees. The center of the pulley 26 is so located on the radius 31 that the intersection of this radius and of the cable 27 laid on the pulley is 1.78 inches beyond the arc of the rocker. When the furnace is rocked so far as to bring the radius 31 to a vertical position the corresponding point on the pulley, will, therefore, project downward a distance of 1.78 inches below the horizontal line on the surface of the track 5. And as the tilting is continued to the extreme position the same point on the pulley will be lifted above the track to approximately the starting position, a distance of 1.78 inches. Thus the movement of the end of the part 27 in a vertical direction is so slight that this part will be substantially parallel for all positions, as above explained.
- Various other styles of flexible connection between the motor and the electrode may be used having a part extending from the motor to the pulley 26, or to some other direction-changing device, mounted on the furnace, and having another part extending therefrom to the electrode, the pulley or direction-changing device being such that the point of engagement of the flexible means therefor is substantially the same position when the furnace is tilted as when it is upright; and preferably is in this same position throughout the tilting movement of the furnace; so as to avoid substantial movement of the electrode with reference to the furnace.
- In further explanation of the location of the sheave or pulley 26, it will be understood that as the furnace rocks the center of the sheave moves horizontally and vertically and the sheave itself is turned through an angle equal to that on which the furnace is rocked. That is, the sheave does not turn on its supporting stud, but the sheave and stud together are rotated about their axis. This rotation of the sheave unwraps from it a certain length of the cable 27, without affecting the portion of the cable from the sheave to the electrode. The portion unwrapped is converted from an arc to a straight line. The dimensions and locations of the parts are so chosen that the horizontal component of the movement of the center of the sheave is equal to the arc of the sheave through which it is turned, which is equal to the length of cable unwrapped. The straightening of this portion of the cable has, therefore, required no rotation of the sheave on its stud and has neither pulled nor slackened the portion of the cable extending from the sheave up to the electrode.
- Though I have described with great particularity of detail an embodiment of my invention, yet it is not to be understood that the invention is restricted to the particular embodiment disclosed. Various modifications thereof in detail and in the arrangement of the parts may be made by those skilled in the art without departing from the invention, as defined in the following claims.
- What I claim is—
1. The combination with a tilting electric furnace of electrode adjusting mechanism for said furnace, said mechanism comprising a motor mounted independently of the furnace and a flexible connection extending from said motor to the electrode, one part of said connection extending from the motor to a member mounted on the furnace and engaging said member at a point which is substantially unchanged when the furnace is tilted and another part of said connection

- extending from said point of engagement to the electrode, whereby the latter is held in substantially the same position with reference to the furnace when the furnace is tilted as when it is upright.
2. The combination with a tilting electric furnace of electrode adjusting mechanism for said furnace, said mechanism comprising a motor mounted independently of the furnace, a pulley mounted on the furnace and a cable operated by said motor and extending over said pulley to its electrode, said pulley being located in such a position on the furnace that as the latter is tilted the electrode is held in substantially the same position with reference to the furnace as when it is upright.
3. The combination with a rocking electric furnace of electrode adjusting mechanism therefor, said mechanism comprising a motor mounted independently of the furnace, a flexible connection extending from said motor to its electrode, one part of said connection extending from the motor to a member mounted on the furnace and engaging said member at a point near the curve of the rocker which has a minimum vertical motion and another part of said connection extending from said point of engagement to the electrode.
4. The combination with a rocking electric furnace of electrode adjusting mechanism therefor, said mechanism comprising a motor mounted independently of the furnace, a flexible connection extending from
- said motor to its electrode, one part of said connection extending from the motor to a sheave mounted on the furnace and engaging said sheave at a point near the curve of the rocker which has a horizontal motion substantially equal to the arc of the sheave through which it is turned in the rocking of the furnace, and another part of said connection extending from the sheave to the electrode.
5. The combination with a rocking electric furnace of electrode adjusting mechanism therefor, said mechanism comprising a motor mounted independently of the furnace, a flexible connection extending from said motor to its electrode, one part of said connection extending from the motor to a sheave mounted on the furnace and engaging said sheave at a point near the curve of the rocker which has a horizontal motion substantially equal to the arc of the sheave through which it is turned in the rocking of the furnace, and another part of said connection extending from the sheave to the electrode, the point of engagement of the connection with the sheave being also located so as to have a minimum vertical motion whereby the electrode is held in substantially the same position with reference to the furnace when the latter is tilted as when it is upright.

In witness whereof, I have hereunto signed my name.

JAMES H. GRAY.
